SAFETY PIN HOLDER

Robert Francis Kenney, Gardner, Mass.

Application April 14, 1951, Serial No. 221,054

3 Claims. (Cl. 211—106)

1

This invention relates to a holder for safety pins.

There are many problems involved in the requirement of the average household that a supply of safety pins be kept on hand, yet stored safely. The safety pins become scattered and lost and present a danger to children who may pick them up, especially if left in an opened condition. It is ordinarily desired that these pins be held in a supply near a bathinette or in the kitchen or bedroom where a child is being bathed or dressed. They should, of course, be so conveniently displayed and arranged that they may be readily picked up one at a time without disturbing the other pins in the supply.

It is the primary object of this invention to provide a device which will hold a supply of safety pins in an easily removed condition and yet will normally secure them against accidental loss and hold them particularly in a closed and safe condition.

Another object is to provide a safety pin holder capable of being secured to a wall or other support which will hold a considerable supply of safety pins of different sizes as required and which provides for ready loading and removal of the pins.

A further object is to provide a simple and economically constructed device of this general type which may carry several sizes of safety pins in a separated relationship and provide for their separate removal. Other objects will be made apparent in the following disclosure.

Referring to the drawings illustrating one embodiment of this invention:

Fig. 1 is a substantially full size perspective view of the safety pin holder;

Fig. 2 is a side elevation thereof, partly in section, and shown as applied to a wall; and

Fig. 3 is an enlarged sectional detail taken on the line 3—3 of Fig. 2.

In accordance with this invention, I have provided a support having a wire resiliently carried thereon which is so arranged that a safety pin may be readily threaded onto the wire and may be easily but not accidentally removed therefrom. Although the device may be made transportable and not mounted in a stationary position, it is preferred that it be arranged for mounting on a wall or other support. The device comprises at least one wire carrier for the safety pins, and preferably two or more wires 10 on which the safety pins 12 may be mounted. Each wire 10 is carried on a central depending vertical post 14 and arranged to lockingly engage a horizontal

5 supporting bar 16 which holds the safety pins on the wire and prevents their accidental removal. The metal bar 16 is shown as an L-shaped flanged member or angle iron having an upright portion 18 provided with holes 19 arranged for the insertion of nails or screws 20 by which the device is secured to a wall or other support 21.

10 Each of the wires 10, which is made of a flexible but stiffly resilient metal, is substantially U-shaped and secured centrally intermediate its ends to the post 14 at a point well below the horizontal flange 16. The two upper ends 22 of each wire are preferably inturned towards the vertical flange 18, but spaced therefrom, so as to minimize any danger to the user of the device. As 15 illustrated, each wire engages the bar flange 16 well below the inturned end and within a slot or notch 24 in the flange. The wire is so shaped that, because of its resiliency, it fits snugly 20 against the inner end of the slot 24, so that the safety pin mounted on the wire will not escape except when the wire is forcibly bent outwardly from that slotted portion of the flange. The bar 16 and slot, therefore, form a support and locking 25 member which positions and holds the free end of the looped wire 10 in a closed carrier position.

To provide the required resilient mounting, each wire, as shown in Fig. 3, is passed through a cylindrical hole 26 in the post 14 of a size within 30 which the wire fits. The wire, after being inserted in that hole, is bent downwardly to hug against the sides of the post, and a suitably shaped metal sleeve 28 is clamped over the bent-down portions of the wire and is soldered in place 35 by a silver or other suitable solder. Just below the sleeve 28 each free end of the wire turns outwardly, backwardly and then upwardly in an extended loop so shaped that the outer portions of each wire are normally substantially parallel 40 with each other and the central post 14, so that when not engaging the flange 16 each face end of the wire extends in the general direction of the flange 18. Owing, however, to the width of the horizontal flange 16, the wire is forced forward 45 into the bent shape of Fig. 2 when it is engaged in the slot 24. The resiliency of the wire thus bent holds it firmly in the slot.

The slot 24 is preferably made wide enough so 50 that a safety pin may be threaded onto the top of the wire around the inturned end 22 and down through the slot 24 without requiring that the wire be bent out of the slot. That is, the slot may be as large as the lateral dimensions of the safety pin, so that the wire 10 needs to be bent forward only enough to let the pin wire slip between the

slot wall 24 and the carrier wire 10. The slots 24 may have different widths and depths, so that they will fit safety pins of different sizes. For example, the inner wire 10 may ride in a comparatively small slot 24 which is just large enough to take a small safety pin, and the outer wire 10 may rest in a wire slot which will permit a larger safety pin to be inserted into place without requiring that the wire be sprung out of the slot. However, in either case, the wire is held tightly against the back of the slot by its resiliency so that the safety pins cannot escape, even if the device is not suspended in the manner illustrated.

The post 14 is preferably provided with a head 30 which is so arranged that the post may be mounted in a hole in the flange 16 and the parts soldered in place to form a rigid structure. The drawing shows two wires 10 secured to the post 14, one spaced well above the other, so that the pins on the upper wire will hang free from interference with those on the lower wire. The loops of the wires 10 are of such sizes and shapes that the free ends of the wires 10 are substantially parallel with one another, but with the upper wire inside of and well spaced from the outer wire, as illustrated. These two wires form loops which are symmetrical but of different sizes.

Since it is desirable that the wire 10 does not touch any wall surface on which it is supported, the horizontal flange 16 is preferably tilted up through a slight angle, such as 2°, and this tilts the post 14 slightly forward and thus leaves the two rearwardly bent loops of the wires out of contact with the wall 21, as shown in Fig. 2. Also, the free ends of the wires 10 project far enough above the flange 16 so that the weight of the safety pins loaded thereon will not bend the wires down enough to permit the pins to escape. The inturned end 22 of each wire would engage the flange and prevent such accidental escape of the pins. It will be appreciated that this device may be left transportable and not secured to a wall, in which case the housewife may place it in her work basket, or as desired. The resilient wires are materially smaller than the spring loop of the safety pin so that the latter may be threaded on the wire and cannot escape, even if the safety pins should become unhooked.

Various materials may be employed for this construction, but it is desirable that the wires 10 be made of a strong and preferably resilient steel wire so that the parts will not readily bend out of shape. A 22 gauge steel music wire having a diameter of 0.049 has been found suitable for the purpose. The post 14 may be of any suitable material, such as a wire of about $\frac{1}{8}$ " in diameter and which is heavy enough to hold the wires 10 firmly positioned at its central and lower support.

It will now be appreciated that a supply of different sizes of safety pins may be readily stored on this device and that they will be easily

available for use, and especially where the device has been initially mounted on the wall or the side of the bathinette or other piece of furniture. The carrier wires are sufficiently strong and have enough resiliency to make it difficult for a small child to remove the safety pins, and yet they may be obtained as needed. Many other advantages will be readily apparent. It will also be appreciated that various modifications may be made in this construction within the scope of this invention. Hence the above disclosure is to be interpreted as describing a preferred embodiment of the invention and not as imposing limitations on the appended claims.

I claim:

1. A safety pin holder comprising a horizontal bar adapted to be secured on a fixed support, a post secured to the bar and depending therefrom, a resilient wire secured to the post intermediate the wire ends and at a point remote from the bar, the wire being bent into a loop at each side of the post and having two free in-turned ends resiliently engaging the bar, said bar having slots in which the free wire ends normally rest and are thereby positioned.

2. A safety pin holder having a horizontal bar, a depending post centrally mounted on the bar, said post having a hole therethrough remote from the bar, a resilient wire mounted centrally within the hole and rigidly secured to the post, said wire having two free ends at opposite sides of the post bent outwardly and upwardly from the post and into engagement with the bar, the bar having spaced slots in which the free ends of the wire are resiliently secured, each slot being large enough to permit a safety pin to be mounted on the wire without removing the wire completely from the slot.

3. A device according to claim 2 comprising two wires mounted on the post which are spaced from one another and have substantially parallel ends engaging slots in the cross bar at spaced points, thereby forming four spaced symmetrical loops carried on the post which may separately support four sets of safety pins.

ROBERT FRANCIS KENNEY.
